[57] CLAIM

The ornamental design for a food service trailer body, as shown and described.

DESCRIPTION

FIG. 1 is a left side and front perspective view of a food service trailer body showing my new design, it being understood that the broken lines are for illustrative purposes only and form no part of the claimed design;

FIG. 2 is a top plan view thereof;

FIG. 3 is a front elevational view thereof;

FIG. 4 is a left side elevational view thereof, the right side being symmetrical; and,

FIG. 5 is a rear elevational view thereof.

The bottom plan view is omitted, the trailer bottom being plain and unornamented.
